UNITED STATES PATENT OFFICE.

RALPH DORITY, OF WASHINGTON, DISTRICT OF COLUMBIA, AND HAROLD W. BREINING, OF BROOKLYN, NEW YORK, ASSIGNEES OF ONE-THIRD TO GEORGE EDWIN IJAMS.

COMBINED STATEMENT AND RETURN ENVELOP.

1,401,324.

Specification of Letters Patent. Patented Dec. 27, 1921.

Application filed March 1, 1921. Serial No. 448,938.

To all whom it may concern:

Be it known that we, RALPH DORITY and HAROLD W. BREINING, citizens of the United States of America, residing, respectively, at 5 Washington, District of Columbia, and Brooklyn, in the county of Kings and State of New York, have invented certain new and useful Improvements in Combined Statement and Return-Envelops, of which the following is a specification, reference being had therein to the accompanying drawings.

This invention relates to statement and return envelops and it has for its object to provide a device of this nature by virtue of 15 which the work incident to the sending out of monthly statements by gas companies, electric light companies and like public utilities may be greatly reduced and the chances of error in giving persons making remittances proper credit, will be largely eliminated.

While the envelop of the present invention has a wide range of usefulness in the field indicated, its use is not limited thereto since 25 it may be employed in any connection where a statement or bill is to be sent and a remittance is to be received.

Further objects and advantages of the invention will be set forth in the detailed description which follows.

In the accompanying drawing:

Figure 1 is a front view of an envelop constructed in accordance with the invention; 35 Fig. 2 is a perspective view looking from the rear side of the envelop and with an intervening flap folded to expose certain of the other parts; and

Fig. 3 is a vertical sectional view.

Like numerals designate corresponding 40 parts throughout the several figures of the drawing.

The device of the present invention consists of an envelop comprising a body portion 5 having the front wall 6 and rear wall 45 7. A closure flap 8 is provided with mucilage or like sealing medium indicated at 9. So far the structure is like any ordinary envelop but it differs from other envelops with which we are familiar in that we provide an additional flap 10 that is attached

to the rear wall 7 by a weakened line 11. The outer face of this flap 10 carries a statement form 12 and the outer face of the rear wall 7 is provided with a corresponding statement form. By inserting a piece of carbon paper between the flap 10 and the rear wall 7, the particular material filled in upon the form 12 will be reproduced upon the statement form 13 upon the outer face of the rear wall 7. Thus the statement will be in 60 duplicate but one statement will be detachable and the other will constitute an integral part of the envelop and will lie in such position as to be concealed when the flap 8 is secured in closed position by the mucilage 65 9. The outer face of the front wall of the envelop bears a return address, such as is indicated at 14, and the statement form 12 bears address matter, such as is indicated at 15, and which lies in such position that 70 when the entire structure comprised in the statement and the return envelop is inserted in an entirely separate sight envelop the address matter will be visible through the opening of the sight envelop.

Since so many people pay their bills by check, it is now the custom of public utility companies and the like, to send out their bills in such shape that the part showing the service rendered may be retained by the 80 customer and another part may be detached and sent back to the company. Under these circumstances it is considered that the customer's check is sufficient receipt and no receipt is sent unless the customer requests it. 85 The device of the present invention admirably lends itself to use in the relation indicated and the method of use is as follows:

The return address 14 represents the address of the company sending out the statement and return envelop. By folding the flap 8 down over the front of the envelop the address matter 15 will, when the statement and return envelop is placed in an ordinary sight envelop be visible through the opening of said sight envelop, as before stated, and the postman will deliver the sight envelop with the statement and return envelop therein to Mr. Richard Gibson, 1012 East Vine street, Detroit, Michigan. The cus- 100

5 tomer upon receiving this statement and return envelop detaches the slip 10 along the weakened line 11 and retains the same as his memorandum and receipt. He then places his check for the amount of the statement in the body of the envelop, seals the flap 8, which then conceals the statement form upon the outer face of the rear wall 7 and mails this return envelop back to the sender. This 10 not only insures that remittances returned to pay the amount of the statement will be properly addressed and properly received, but it insures that there will come back with the check or other remittance, the name of 15 the person sending the remittance and an itemized statement of what the money is for.

20 While we may secure the duplicate upon the rear wall 7 by placing a sheet of carbon paper between the flap 10 and said rear wall, the invention contemplates covering the rear face of the flap 10 with transfer material, such as carbon, as indicated at 16.

25 A consideration of the procedure at present followed by some of the public utilities companies will make clear the marked advantages flowing from the use of this device. Under present practice there is provided first an ordinary sight envelop; second a return envelop, that is an ordinary envelop 30 with the address of the company printed thereon; and third, as an entirely separate unit, a bill comprising two parts, one of which is separable from the other and one part of which is to be retained by the customer and the other part is to be sent back with the check or other remittance. It has been found that very frequently customers 35 do not use the return envelop but address envelops of their own with the possibility 40 of making mistakes in the address, other customers use the return envelop but send merely their check and do not return the part of the statement that is intended for the company, thus necessitating a search in 45 the records to determine how the check is to be applied.

50 The device of the present invention obviates the foregoing difficulties by so associating the part that is to be returned to the company, with the return envelop, that the two cannot be separated, thus insuring that when the return envelop comes back something will come with it that will show how 55 the money is to be applied and who sent it. At the same time it leaves in the customer's hands a statement showing what it is he has paid for and this of necessity must be an exact copy of the statement that is returned to the company because it is a carbon copy 60 of the same. We also contemplate the provision of a weakened line 17 about the statement form 13 to permit this form to be readily detached from the remainder of the envelop for filing, if desired.

65 From the foregoing description it will be

seen that we have devised a unitary and integral structure which will facilitate the keeping of accounts of the character indicated and will avoid, or at least largely reduce, the possibility of mistakes.

70 It is to be understood that the invention is not limited to the precise construction set forth but that it includes within its purview whatever changes fairly come within either the terms or the spirit of the appended 75 claims.

Having described our invention, what we claim is:

1. A mailable statement and return envelop comprising a body portion and a sealing flap and bearing duplicate statement forms, one of which is detachable and the other of which is upon an integral part of the envelop, the detachable statement form being so related to the body of the envelop 80 as to leave the latter unimpaired for mailing after the detachable form has been detached.

2. A structure as recited in claim 1 where- 85 in the detachable statement form bears address matter in a position to be visible through the sight opening of a sight envelop when inserted therein.

90 3. A mailable statement and return envelop comprising a body portion, a sealing flap and an additional flap, the latter flap and a portion of the envelop bearing duplicate statement forms, one of which is detachable and the other of which is upon an integral part of the envelop, said sealing flap 95 concealing the last named statement form, when folded to position to close the envelop.

100 4. A mailable statement and return envelop comprising a body portion, a sealing flap and a detachable flap secured to the body of the envelop along the upper edge of the rear wall of the body of the envelop, said detachable flap and the rear wall of the body of the envelop bearing duplicate statement forms.

105 5. A structure as recited in claim 4 where- 110 in the inner face of the detachable flap is provided with transfer material.

115 6. A structure as recited in claim 4 where- in said sealing flap is of a position to over- 118 lie and conceal the rear face of the envelop when the envelop is sealed for mailing.

7. A structure as recited in claim 4 where- 120 in the front wall of the envelop is provided with a return address.

8. A structure as recited in claim 4 where- 125 in the front wall of the envelop is provided with a return address and the statement form upon the detachable flap comprises address matter in a position to be visible through the sight opening of a sight envelop when the statement and return envelop are placed therein.

9. A mailable statement and return envelop comprising a body portion adapted 130

to receive an object to be mailed, and a sealing flap of such shape as to substantially cover the rear wall of the envelop when sealed down thereon, in combination with 5 a detachable flap bearing a statement form and overlying the rear face of the body portion of the envelop to permit of the transfer of matter entered upon said statement form, to the said rear face of the body portion. In testimony whereof we hereunto affix our signatures.

RALPH DORITY.

HAROLD W. BREINING.
